ABSTRACT

A sump drain includes a chamber having an inner sidewall with a diameter of at least about 18 inches and an outer sidewall, and a circular opening between the sidewalls preferably about an inch wide and optionally having a grid cover. Preferably the inner sidewall has ports extending inwardly to radial conduits to a central hub for tying into a pool or spa filtering system, with the central hub operating as a clean out and having a removable cap. Plaster substantially fills the space between the chamber and the central hub, such that the sump drain attractively blends in with the pool or spa floor. When installed, the top opening is preferably substantially flush with the pool or spa floor while being safely unblockable. And the sump drain preferably further includes channels both outboard and inboard from the chamber top opening and around the central hub.

LOW PROFILE CIRCULAR DRAIN WITH WATER STOP FOR SWIMMING POOL

RELATED APPLICATIONS

This application is a continuation of U.S. patent application Ser. No. 15/863,236 entitled "Low Profile Circular Drain With Water Stop For Swimming Pool," now U.S. Pat. No. 10,214,930, which is a continuation of U.S. patent application Ser. No. 15/392,345, now U.S. Pat. No. 9,869,103, a continuation of U.S. patent application Ser. No. 13/794,376, now U.S. Pat. No. 9,540,837, which claims priority to provisional application No. 61/660,566 filed Jun. 15, 2012 entitled "Low Profile Circular Drain Covers," and to provisional application No. 61/734,267 filed Dec. 6, 2012 entitled "Channel Drain With Water Stop."

BACKGROUND

Twin 7-Year Old Virginia Graham Baker was the granddaughter of former Secretary of State James Baker III. In June 2002 she became stuck to the hot tub drain and was unable to pull herself free and she drowned. After her tragic death the family lobbied Congress for a law to require anti-entrapment drain covers and other safety measures. As a result, The Virginia Graham Baker Pool & Spa Safety Act ("VGB Act") was enacted in December, 2007. The 2007 VGB Act changed everything for those in business of providing swimming pool and spa suction outlets or drains. Among one of the ways of complying with the Act was separating two drains by more than three feet, such that a single individual could not likely block both drains with his or her body and become stuck. This also led to increased popularity of channel drains, rectangular and longer than three feet, which accomplished this objective but looked unsightly.

Even before the VGB Act, pool manufacturers were concerned about the aesthetic appearance of drains and were developing products and methods towards making drain covers more attractive. Among products available were small approx. 12 inch diameter round covers having a recessed upper surface forming a cavity to receive aggregate material matching the aggregate surface of the pool. Among disadvantages of this product were that the aggregate material was retained inside a portion of the cover itself, such that changing covers requires filling the new cover with matching new batch of the aggregate material. And also, these small drains are subject to being damaged by being kicked by swimmers and users of hot tubs.

Pool drains or sumps, as currently known in the art, generally comprise a plastic or fiberglass body including a chamber into which water flows from the pool as it gets recycled through the pool's pump and filter. The chamber includes an opening, or outlet port, that connects to a pipe extending to the pool pump and filter apparatus. Pipes are typically installed in gunite or shotcrete material forming the supporting walls of the pool. The terminal end of a pipe is then encased in plaster along with the drain to which it is connected. The plaster covers the gunite or shotcrete and serves as a barrier between water in the pool and the gunite or shotcrete.

As alluded to above, elongate channel sumps are popular in view of their compliance with the VGB Act, requiring swimming pool and spa sumps to prevent a person's body from covering the entire sump intake and becoming entrapped. Anti-entrapment channel sumps generally comply with the VGB Act by providing multiple intake ports,

and being of a sufficient length that the ports cannot be simultaneously blocked, i.e., if one intake port is blocked, the other intake ports allow water to continue to flow into the pump and filtering system.

5 A problem with pool sumps, particularly elongated channel sumps, is that the plaster into which these large sumps are embedded forms cracks over time. One area most prone to form cracks is where the pool sump and plaster meet. Water may seep into the surrounding plaster and then down into the supporting walls of the pool causing damage. It therefore would be advantageous to provide a pool sump that helps prevent water from migrating down cracks as they form between the pool sump and the plaster surrounding it.

15

SUMMARY

A sump drain for connecting to a filtering system and embedding in the plaster floor of a swimming pool or spa includes an annular or ring-like shaped chamber having an inner sidewall with a diameter of at least about 18 inches and an outer sidewall, and an annular top opening between the sidewalls preferably about an inch wide. The chamber, preferably the inner sidewall, has a plurality of ports to radial conduits extending inwardly to a central hub for tying into the pool or spa filtering system, with the central hub operating as a clean out and having a removable cap.

20 The sump drain further preferably includes a circular grid, sized to cover the top opening and having a multiplicity of openings in it, or alternatively the drain may be configured to provide a narrow gap between inner and outer sidewalls and be used without a grid cover. The sump drain is configured such that upon installation plaster substantially fills the space between the chamber and the central hub; thereby the sump drain attractively blends in with the pool or spa floor. When the drain is installed the top opening is 25 preferably substantially flush with the pool or spa floor, and being of sufficiently large size to be unblockable. The sump drain preferably further includes channels both outboard and inboard from the chamber top opening, to help prevent water from passing through the plaster and into the shotcrete of the pool or spa.

30 Installing the sump drain in a plaster floor of a swimming pool or spa for connection to a filtering system, includes the steps of providing the sump drain having the generally annular-shaped chamber with a diameter of at least about 18 inches and conduits which extend to the central hub; placing the sump drain in the floor of the pool or spa near the filtering system; connecting the central hub to the filtering system; and embedding the sump drain in the pool or spa including covering it with plaster between the annular chamber and the hub. Preferably prior to embedding the sump drain in the pool or spa, a temporary cover on the sump drain prevents plaster from getting inside the chamber.

45

BRIEF DESCRIPTION OF THE DRAWINGS

50 FIG. 1 is a perspective view of a preferred embodiment circular drain assembly.

55 FIG. 2 is a side elevation view of the preferred embodiment circular drain assembly.

60 FIG. 3 is a top plan view of the preferred embodiment circular drain assembly.

65 FIG. 4 is a perspective exploded view of the preferred drain assembly with the temporary plaster cover.

FIG. 5 is an exploded view of the preferred drain assembly with the grid cover, and also showing the removability of the center cover.

FIG. 6 is a perspective view showing the preferred drain installed into the surface of a pool with the plaster cover.

FIG. 7 is a section view taken from FIG. 6.

FIG. 8 is a perspective view showing the preferred drain with the grid cover installed in a pool.

FIG. 9 is a section view taken from FIG. 8.

FIG. 10 is an enlarged section view showing the grid cover installed and the water stop feature.

FIG. 11 is an enlarged section view showing the center cover installed and again the water stop feature.

FIG. 12 is a perspective view of the alternate embodiment circular drain assembly.

FIG. 13 is a perspective view of the alternate drain installed in a pool.

FIG. 14 is section view taken from FIG. 13.

FIG. 15 is an enlarged portion of FIG. 14.

FIG. 16 is an enlarged section view of the water stop feature.

DETAILED DESCRIPTION

Referring to drawing FIGS. 1-11, the low profile circular drain 10 or suction outlet or sump of the preferred embodiment is disclosed. As best shown in FIGS. 1-3, the drain 10 has an annular ring-shaped body or chamber 12 although optionally the drain 10 may be other preferably rounded shapes such as oval or merely with rounded corners (not shown). The chamber 12 has an inner sidewall 14 having a diameter of about 18 inches (dimension D as labeled in FIG. 7) and outer sidewall 16 having an outside diameter of about 21 inches, and the depth of the chamber from top to bottom is about 3.5 inches. The top side of the chamber 12 is generally open, forming an annular or ring-shaped space 18 between the sidewalls 14, 16, which may be sized to receive a corresponding circular grid cover 22. The grid cover 22 may include a large number (here there are about 150) rectangular, radial slots 24. Optionally, the cover 22 may have other types of openings (not shown), most anything that allows water to pass through while stopping larger debris such as leaves.

The inner sidewall 16 has multiple openings or outlet ports 26 connecting to one or more conduits or pipes 28. The conduits 28 extend radially inward to a central hub 30 that connects to the pump and filtering system 32 in the floor of the pool or spa. The hub 30 preferably has about a 2.5 inch inner diameter, and its length from the bottom of the chamber 12 to the end is about 2.5 inches. The top side of the hub 30 includes a cap 34 on which a manufacturer's logo, here ABC, may be displayed, and the cap 34 is removable for purposes of cleaning out the drain 10 should it become clogged with debris. It's held on by a pair of flat head Phillips screws 36 (FIG. 5).

Next referring to FIGS. 4-12, installation of the drain 10 as well as further features may be described. FIG. 4 shows a plastering cover 38 which is temporarily placed in the chamber 12 opening 18, to keep plaster from getting into the chamber 12 when the drain 10 is being installed in the floor of a pool or spa. The plastering cover 38 preferably includes several, at least two thumb/index finger holds 40 for facilitating later removal of the plastering cover 38 once the drain 10 is embedded in the pool or spa. FIG. 5 shows the grid cover 22 which is then added, held on by eight (8) screws 36. FIG. 6 shows the drain 10 being installed in the plaster surface 42 floor of a swimming pool or spa, with the plaster 42 covering up the temporary cover 38 and the center hub cap 34. Optionally, it may also be installed vertically in a lower wall of a pool or spa (not shown). FIG. 7 shows the

top side opening 18 into which the plastering cover 34 fits, along with the hub cover 34 (also see FIG. 12), being substantial flush with the plaster surface 42. FIG. 8 shows that there is a substantial amount of plaster 42, as well as the underlying gunite or shotcrete material 44, between the 5 annular chamber 12 and the center hub 30. With the drain 10 being installed in this fashion, it offers improved structural integrity in that any load from a swimmer's foot or occupant of a hot tub will impact only a small portion of the drain 10 and tend to be absorbed by the surrounding floor or wall of the pool or spa.

FIGS. 9, 10 shows the plastering cover 34 removed and replaced with the grid cover 22. As indicated in FIG. 5, the grid cover is secured in place in the top opening 18 by 15 several Phillips head screws 36. Thus, the grid cover 22 and center cap 34 are the only parts of the drain 10 seen upon installation, and they blend into the plaster surface 42 of the floor of the pool or spa. FIG. 11 shows the cover 22 is substantially flush with the surrounding plaster 42, and as 20 per FIG. 12 the center hub cap 34 is similarly substantially flush with the plaster 42 floor. [FIGS. 11, 12 also show water stops 50, 60 for stopping any water that intrudes between the sump 10 and plaster 42 into which the sump 10 is embedded. In the preferred embodiment the water stop 50, 60 is 25 tray-shaped like a gutter or channel 52, 62 and extends around the sump 10 to collect water seeping into cracks between the sump 10 and the plaster 42. The water stop 50 also serves to anchor the sump 10 in the plaster 42. The gutter or channel 52 is located inboard the grid cover 22, and 30 the same channel 52 is built in around the hub cover 34. A slightly differently configured water stop 60 is located outboard the grid cover 22, as the gutter or channel 52 is molded into the chamber body 22 adjacent to the screws 36 which attach the cover 22. Each water stop 50, 60 preferably 35 includes a horizontal shelf 54 and a vertical wall 56, again to catch water migrating between the sump 10 and the plaster 42 in which the sump 10 is installed. The vertical wall 56 may extend above and below the horizontal shelf 54, providing an effective anchoring mechanism during sump 10 40 installation.

Now also referring to FIGS. 13-16, a second alternate embodiment 110 is discussed. This drain 110 has a round sump body 112, and an inner leaf trapper ring 114 and an outer leaf trapper ring 116. The leaf trapper rings 114, 116 are located concentric to each other and provide a narrow, circular gap 118 (d equals about 0.875 inches wide in FIG. 16) for water to pass but small enough to prevent larger objects from passing such as leaves. As best seen in FIGS. 15, 16, the leaf trapper rings 114, 116 have upper surfaces 120, 122 which are substantially flat and approximately align with one another. This embodiment 110 may include a temporary plaster cover 36 as described above; it does not include the circular grid cover 22. The end result is a highly effective drain system flush with the surface of the pool, with 55 plaster or other aggregate material having the same color and texture both inside and outside the concentric rings or circular grid. The drain has a nearly invisible, pleasing aesthetic appearance. The drain is a safe, VGB compliant drain, large enough to be unblockable by a single person. The drain is rugged, not susceptible to being easily damaged, and the water stop feature helps maintain the structural 60 integrity of the surrounding plaster in the pool or spa floor for many years.

While the apparatus and method have been described in detail with reference to specific embodiments thereof, it will be apparent to one skilled in the art that various changes and modifications can be made therein, without departing from

the spirit and scope thereof. Thus, it is intended that the present description cover that modifications and variations of the apparatus and method provided, while it is only the appended claims and their equivalents which define the scope of the invention.

What is claimed is:

1. A low profile drain for installation in a surface of a swimming pool or spa formed of a surface material and having a drain inlet, the low profile drain comprising:

a sump embedded in the surface when installed, the sump

forming a top side defining an annular top opening no less than about eighteen inches in inner diameter exposed through the surface, the sump forming an outer sidewall and an inner sidewall on opposite sides of the annular top opening, the outer sidewall having an upper peripheral edge about the annular top opening;

the sump having a tray-shaped water stop extending radially therefrom and adjacent to the upper peripheral edge for catching migrating water and for embedded anchoring in the surface when installed;

the sump extending to a central connection to the drain inlet in the surface when installed, the sump defining an open chamber spanning beneath the annular top opening to receive water admitted therethrough, the sump being configured to maintain open communication between the annular top opening and the central connection, the annular top opening defined to contiguously extend fully about the central connection;

the sump being configured to receive water admitted through the annular top opening and guide the water to the central connection through portions of the sump embedded in the surface when installed; and

the sump being configured with the annular top opening encircling surface material substantially filling the space inside the inner sidewall when the low profile drain is installed, the surface material and the annular top opening being substantially flush with the surface when the low profile drain is installed, and the sump except the annular top opening being substantially covered by the surface material to blend in with the surface when the low profile drain is installed.

2. The low profile drain recited in claim 1, wherein a portion of the sump is removable from above the central connection to access the drain inlet for purposes of cleaning out the drain inlet.

3. The low profile drain as recited in claim 2, wherein the central connection includes a hub extending upwardly to be about coplanar with the top annular opening.

4. The low profile drain as recited in claim 3, wherein the portion of the sump removable from above the central connection includes a central cap no greater than about 2.5 inches in diameter.

5. The low profile drain as recited in claim 1 further comprising a drain cover coupled to the sump to cover the annular top opening.

6. The low profile drain as recited in claim 1, wherein both the inner and outer sidewalls are formed with the water stop, the water stop extending radially inward from the inner sidewall and radially outward from the outer sidewall.

7. The low profile drain as recited in claim 1, wherein the sump defines a ring-shaped chamber, and a plurality of radial conduits extending between the ring-shaped chamber and the central connection.

8. The low profile drain as recited in claim 1, wherein the sump is configured to accept a substantial amount of the surface material between the inner sidewall and the central connection.

9. A low profile drain for installation in a surface of a swimming pool or spa formed of a surface material and having a drain inlet, the low profile drain comprising:

a sump embedded in the surface when installed, the sump forming a top side defining an annular top opening no less than about eighteen inches in inner diameter exposed through the surface, the sump forming an outer sidewall and an inner sidewall on opposite sides of the annular top opening, the outer sidewall edge about the annular top opening;

the sump having a tray-shaped water stop extending radially therefrom and adjacent to the upper peripheral edge for catching migrating water and for embedded anchoring in the surface when installed;

the sump extending to a central connection to the drain inlet in the surface when installed, the sump being configured to maintain open communication between the annular top opening and the central connection, the annular top opening defined to contiguously extend fully about the central connection;

the sump being configured to receive water admitted through the annular top opening and guide the water to the central connection through portions of the sump embedded in the surface when installed; and

the sump being configured with the annular top opening encircling surface material substantially filling the space inside the inner sidewall when the low profile drain is installed, the surface material and the annular top opening being substantially flush with the surface when the low profile drain is installed, and the sump except the annular top opening being substantially covered by the surface material to blend in with the surface when the low profile drain is installed;

wherein the water stop includes a horizontal shelf and a vertical wall collectively forming a gutter, the water stop being endlessly looped about the outer sidewall.

10. A sump drain having a rounded anti-entrapment configuration for partially embedded installation within a surface of a pool or spa formed of a surface material and having a drain inlet, the sump drain comprising:

a body defining a water receiving structure having a substantially circular intake opening for admitting water therethrough, the intake opening having an inner diameter of at least 18 inches, the body having an upper peripheral edge about the intake opening, the body defining an open chamber spanning beneath the intake opening to receive water admitted therethrough, the body being configured to be embedded within the surface and attach to the drain inlet when installed;

the body having a gutter portion formed to extend radially from the body and adjacent to the upper peripheral edge for catching migrating water, the gutter portion configured for embedded anchoring in the surface; and the body maintaining open communication from the intake opening to the drain inlet when installed, and the body configured to guide the water admitted through the intake opening to the drain inlet of the pool or spa; and

the body being configured to receive a substantial amount of the surface material inboard of the intake opening and up to being about flush with the surface of the pool or spa when the sump drain is installed, such that the body is substantially covered by the surface material and blends in with the surface;

wherein the body is configured such that the drain inlet is selectively accessible through the body with the sump drain installed in the surface.

11. The sump drain as recited in claim 10 further comprising a drain cover coupled to the body to cover the intake opening.

12. The sump drain as recited in claim 10, wherein the gutter portion forms a channel extending contiguously about the intake opening.

13. The sump drain as recited in claim 10, wherein a portion of the body disposed above the drain inlet is removably covered by a central cap about 2.5 inches in diameter for displaying a manufacturer's logo.

14. The sump drain as recited in claim 10, wherein the body defines a plurality of radial parts extending from the intake opening for guiding the water admitted by the intake opening radially inward to the drain inlet.

15. The sump drain as recited in claim 10, wherein the gutter portion forms a channel extending radially from and along an outboard side of the intake opening.

16. A sump drain for installation in a surface of a swimming pool or spa formed of a surface material and having a drain inlet, the sump drain comprising:

an upper part exposed through the surface when installed, the upper part having a first portion forming an outer sidewall and a second portion forming an interior sidewall, the outer sidewall encircling the interior sidewall, the first and second portions being configured for at least partial embedding in the surface, the outer and interior sidewalls defining a contiguous annular top opening therebetween, the interior sidewall being not less than about 18 inches in diameter, the outer sidewall having a upper peripheral edge about the annular top opening, the upper part being formed with a water stop defining a gutter extending radially therefrom and adjacent to the upper peripheral edge;

a central connection disposed radially inward from the contiguous annular top opening of the upper part to be in open communications therewith, the central connection being configured for embedding in the surface of the swimming pool or spa and coupling to the drain inlet when installed; and

a lower part configured for embedding in the surface beneath the upper part when installed, the lower part defining an open chamber spanning beneath the contiguous annular top opening to receive water admitted through the contiguous annular top opening, the lower part in cooperation with the upper part guide the water to the central connection;

wherein the contiguous annular top opening is defined to contiguously extend fully about the central connection and remain substantially flush with the surface when the sump drain is installed in the swimming pool or spa; wherein the upper part is configured to receive a substantial amount of the surface material inside the interior sidewall and up to being about flush with the surface of the swimming pool or spa when the sump drain is installed, such that the sump drain is substantially covered by the surface material and blends in with the surface; and

wherein a portion of the upper part disposed above the central connection is removable to access the drain inlet when installed.

17. The sump drain as recited in claim 16 further comprising a drain cover coupled to the outer and interior sidewalls to cover the annular top opening.

18. The sump drain as recited in claim 16, wherein the water stop extends from the outer sidewall to be endlessly looped about the upper part.

19. The sump drain as recited in claim 16, wherein the upper and lower parts form a ring-shaped chamber therebetween, and further comprising a plurality of radial parts extending between the ring-shaped chamber and the central connection.

20. The sump drain as recited in claim 16, wherein the central connection includes a hub extending upwardly to about the surface when the sump drain is installed, and the removable portion of the upper part includes a central cap covering the central connection to the drain inlet, the central cap being no greater than about 2.5 inches in diameter.

21. A sump drain for installation in a surface of a swimming pool or spa formed of a surface material and having a drain inlet, the sump drain comprising:

an upper part exposed through the surface when installed, the upper part having a first portion forming an outer sidewall and a second portion forming an interior sidewall, the outer sidewall encircling the interior sidewall, the first and second portions being configured for at least partial embedding in the surface, the outer and interior sidewalls defining a contiguous annular top opening therebetween, the interior sidewall being not less than about 18 inches in diameter, the outer sidewall having an upper peripheral edge about the annular top opening, the upper part being formed with a water stop defining a gutter extending radially therefrom and adjacent to the upper peripheral edge;

a central connection disposed radially inward from the contiguous annular top opening of the upper part to be in open communications therewith, the central connection being configured for embedding in the surface of the swimming pool or spa and coupling to the drain inlet when installed; and

a lower part configured for embedding in the surface beneath the upper part when installed, the lower part being disposed to receive water admitted through the contiguous annular top opening and in cooperation with the upper part guide the water to the central connection;

wherein the contiguous annular top opening is defined to contiguously extend fully about the central connection and remain substantially flush with the surface when the sump drain is installed in the swimming pool or spa; wherein the upper part is configured to receive a substantial amount of the surface material inside the interior sidewall and up to being about flush with the surface of the swimming pool or spa when the sump drain is installed, such that the sump drain is substantially covered by the surface material and blends in with the surface; and

wherein a portion of the upper part disposed above the central connection is removable to access the drain inlet when installed;

wherein the water stop includes a horizontal shelf and a vertical wall collectively forming the gutter.

22. A low profile drain for installation in a surface of a swimming pool or spa formed of a predetermined material and coupling to an inlet of a pump and filtering system of the swimming pool or spa, the low profile drain comprising:

a sump embedded in the surface when installed, the sump having a generally rounded shape with a top side having a ring-shaped opening between an outer sidewall and an inner sidewall, the ring-shaped opening spanning a minimum distance of about 18 inches diametrically across the surface when the sump is installed, the outer sidewall having an upper peripheral edge about the ring-shaped opening;

the sump having a channel extending radially therefrom and adjacent to the upper peripheral edge for embedded anchoring in the surface when installed; and the sump having a hub for coupling to the inlet in the surface when installed, the sump defining an open chamber spanning beneath the ring-shaped opening to receive water admitted therethrough, the sump being formed to maintain open communication between the ring-shaped opening and the hub, the sump including portions embedded in the surface when installed and configured to guide water admitted through the ring-shaped opening to the hub; wherein when the sump is installed, the inner sidewall is configured to enclose a portion of the predetermined material of the surface, with the portion of the predetermined material and the ring-shaped opening being substantially flush, and the sump being substantially covered by the predetermined material to blend in with the surface except at the ring-shaped opening.

23. The low profile drain as recited by claim 22, wherein the sump includes a removable portion disposed above the hub for selective access to the inlet for purposes of cleaning out the inlet.

24. The low profile drain recited in claim 23 further comprising a temporary cover for the ring-shaped opening sized to temporarily fit into the sump until all the predetermined material is installed around the low profile drain.

25. The low profile drains as recited by claim 22, wherein the sump defines a ring-shaped chamber, and a plurality of radial parts extending between the ring-shaped chamber and the hub.

26. The low profile drain as recited in claim 22, wherein the sump is configured to accept a substantial amount of the predetermined material between the inner sidewall and the hub.

27. The low profile drain as recited by claim 22, wherein the hub extends upwardly to be about coplanar with the ring shaped opening.

28. The low profile drain as recited in claim 22, wherein the sump has the generally rounded shape thereof selected

from the group consisting of: an oval shape, a circular shape, and a shape defining rounded corners.

29. A low profile drain for installation in a surface of a swimming pool or spa formed of a predetermined material and coupling to an inlet of a pump and filtering system of the swimming pool or spa, the low profile drain comprising:

a sump embedded in the surface when installed, the sump having a generally rounded overall shape with a top side having a ring-shaped opening between an outer sidewall and an inner sidewall, the ring-shaped opening spanning a minimum distance of about 18 inches diametrically across the surface when the sump is installed, the outer sidewall having an upper peripheral edge about the ring-shaped opening;

the sump having a channel extending radially therefrom and adjacent to the upper peripheral edge for embedded anchoring in the surface when installed; and

the sump having a hub for coupling to the inlet in the surface when installed, the sump being formed to maintain open communication between the ring-shaped opening and the hub, the sump including portions embedded in the surface when installed and configured to guide water admitted through the ring-shaped opening to the hub;

wherein when the sump is installed, the inner sidewall is configured to enclose a portion of the predetermined material of the surface, with the portion of the predetermined material and the ring-shaped opening being substantially flush, and the sump being substantially covered by the predetermined material to blend in with the surface except at the ring-shaped opening;

wherein the channel defines a water stop configured for catching migrating water, the water stop includes a horizontal shelf and a vertical wall collectively forming a gutter.

30. The low profile drain as recited by claim 29, wherein the water stop is endlessly looped about the outer sidewall.
